(57) **CLAIM**

The ornamental design for a temporary flex space, substantially as shown and described.

DESCRIPTION

FIG. 1 is a front, right side perspective view of the temporary flex space showing the new design while in an open door position;

FIG. 2 is a rear, right side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a front, right side perspective view thereof;

FIG. 9 is a front, right side perspective view thereof shown while in a semi-open door position;

FIG. 10 is a front, right side perspective view thereof shown while a secondary front door is in an open position;

FIG. 11 is a front, right side perspective view thereof shown while in a closed door position;

FIG. 12 is a front elevation view thereof;

FIG. 13 is a left side elevation view thereof;

FIG. 14 is a right side elevation view thereof; and,

FIG. 15 is a top plan view thereof.

The dashed lines depict surface details that form no part of the claimed design. The dashed lines shown in the interior of the temporary flex space are for purposes of illustrating environmental subject matter that form no part of the claimed design. The bottom plan view was not shown because the bottom of the temporary flex space does not form part of the claimed design.
